HAND BRAKE

Stacy B. Haseltine, Chicago, Ill., assignor to W. H. Miner, Inc., Chicago, Ill., a corporation of Delaware

Original application August 1, 1930, Serial No. 472,218. Patent No. 1,931,655, dated October 24, 1933. Divided and this application September 22, 1933, Serial No. 690,521

4 Claims. (Cl. 254—149)

This invention relates to improvements in hand brakes.

This application is a division of my application, Serial No. 472,218, filed August 1, 1930, on which Patent No. 1,931,655, dated October 24, 1933, has been granted.

One object of the invention is to provide, in a hand brake mechanism including a chain-winding drum, simple and efficient means for arresting the unwinding movement of the chain-winding drum in a predetermined position when the brakes are released.

Another object of the invention is to provide, in a brake mechanism of the character indicated in the preceding paragraph, means for positively stopping the unwinding movement of the chain-winding drum when the brakes are released and so positioning the pivot connection of the chain with the drum that quick take-up of the slack in the brake chain is effected immediately when the drum is rotated in chain-winding direction.

A still further object of the invention is to provide stop means of the character described in the preceding paragraph, which is especially designed for operation in connection with a chain-winding drum having more than one turn of the chain wound thereon in the chain-tightening operation.

Yet another object of the invention is to provide a stop means which effectively stops the rotation of the drum of a hand brake mechanism when the brakes are quickly released so as to prevent reverse winding of the chain thereon, which might otherwise occur due to the momentum of the rotation of the drum.

Other objects of the invention will more clearly appear from the description and claims herein-after following.

In the drawing, forming a part of this specification, Figure 1 is a vertical sectional view of a hand brake mechanism, illustrating my improvements in connection therewith. Figure 2 is a vertical sectional view, on an enlarged scale, corresponding substantially to the line 2—2 of Figure 1, said view being partly broken away.

In said drawing the hand brake mechanism is shown as mounted on the vertical end wall 10 of a railway car and is enclosed within a two-part housing comprising sections 12 and 13. The section 12 forms the cover plate of the housing and the section 13 the housing proper. The section 13 is provided with securing lugs 14—14 by which the same is fixed to the end wall of the car. The housing section 13 is divided into two compart-

ments by a vertically disposed partition wall 11 at right angles to the plane of the end of the car. At the right-hand end, as viewed in Figure 1, the housing has a side wall 20, which is provided with an outwardly projecting closed boss 21. At the inner end, the boss 21 is provided with a bearing opening 22 which receives and forms a journal member for the inner end of a shaft 23 on which the chain-winding drum A is mounted. The opposite end of the shaft 23 has a cylindrical portion 24, which is journaled in a bearing opening 25 provided in the partition wall 11. At the extremity of the shaft 23 to the left of the partition wall 11, as viewed in Figure 1, the same is provided with a clutch member F, which is formed integral therewith. The clutch member F is provided with a plurality of recesses 26—26 which cooperate with a clutch member E. To the left of the clutch member F, the shaft 23 is provided with a cylindrical bearing portion 21, on which a worm wheel B is rotatably journaled. The worm wheel B meshes with a driving worm member C rotated by the operating hand wheel, not shown.

The clutch member E is rotatable about the axis of the shaft 23 and is secured to an operating rod 28 extending through the shaft 23 and projecting beyond the right-hand end of the same, as viewed in Figure 1, said projecting portion being disposed within the hollow boss 21. The projecting portion last referred to has a spring cap 29 fixed thereto, within which a clutch spring H is housed. The inner end of the clutch spring H bears directly on the extremity of the shaft 23, thereby pulling the rod 28 to the right, as viewed in Figure 1. At the outer end, that is, the left-hand end of the rod as viewed in Figure 1, the same is provided with an enlarged portion 30, which extends through an opening 31 in the cover member of the housing. The inner end of the enlarged portion 30 of the rod is engaged within the clutch member E and is secured thereto by a transverse locking pin or rivet 32. As will be evident, the clutch member E is thus secured to the clutch operating rod 28 so as to be reciprocable therewith and is yieldingly held in its extreme right-hand position, as viewed in Figure 1, by the clutch spring H. The clutch member E has a pair of diametrically arranged, laterally projecting, clutch fingers or arms 61—61, which are slidable within openings 62—62 provided in

the worm wheel B and are engageable with the recesses 26—26 of the clutch member F. An operating lever G is pivotally connected at the inner end to a collar or ring 33 which surrounds the outer end of the rod 28, the rod being headed, 55

as indicated at 34, to provide shouldered engagement between the collar and rod. The housing section 13 is open at the bottom so as to accommodate the brake chain 35, which is connected to the brake mechanism proper, not shown, of the car in the usual manner.

My improvements, comprise broadly a stop member K on the chain-winding drum and a co-operating stop shoulder on the housing of the 10 brake mechanism.

In carrying out my improvements, the inner 15 end of the brake chain 35 is connected to outstanding securing lugs formed on the chain-winding drum, by means of a connecting pin 36 extending through said lugs and the innermost link 20 of the chain 35, as shown in Figure 2. The chain-winding drum has the stop member K pivoted thereto, the latter being swingingly supported on the pin 36. The stop member K is provided 25 with a stop face 37 at the right-hand side thereof, as viewed in Figure 2, which cooperates with a transverse stop shoulder 38 formed by the wall section 39 of the housing. The stop member K is of such a size that when it is swung inwardly 30 against the chain-winding drum it will clear the wall 39 of the housing so that the winding drum may be rotated in chain-winding direction without interference. When the chain-winding drum is rotated in an unwinding direction, that is, in 35 a counterclockwise direction, as viewed in Figure 2, the stop member K will swing downwardly through the action of gravity to the position shown in said figure and engage the stop shoulder 38, thereby arresting rotation of the chain-winding drum and preventing rewinding of the chain 40 thereon due to spinning of the same. The stop K is held in position against the drum by the chain being wound over the stop, thereby preventing contact with the shoulder 38 until after the chain has been completely unwound, thus permitting the necessary number of rotations of the drum to completely unwind the chain.

In the operation of my improved hand brake mechanism, in applying the brakes the worm C is rotated to actuate the worm wheel B while the clutch fingers or arms of the clutch member E are held in interlocking relation with the notches of the clutch member F by means of the clutch spring H, thereby causing the chain-winding drum to be rotated when the hand wheel 45 is actuated. To effect quick release of the brakes, the cam lever G is pulled outwardly, thereby pulling the rod 28 to the left, as viewed in Figure 1, against the tension of the spring H, and carrying 50

the clutch member E therewith, thus disengaging the clutch fingers or arms from the clutch member F. Free rotation of the latter and the chain-winding drum is thus permitted, thereby quickly releasing the brakes. As hereinbefore pointed out, in releasing the brakes rotation of the drum is positively arrested and rewinding of the chain on the chain-winding drum is prevented by the stop member K engaging the stop shoulder 38 on the housing.

I have herein shown and described what I now consider the preferred manner of carrying out my invention, but the same is merely illustrative and I contemplate all changes and modifications that come within the scope of the claims appended hereto.

I claim:

1. In a hand brake mechanism, the combination with a chain-winding drum; of a brake chain connected to the drum; operating means for rotating the drum; a gravity-influenced swinging stop member connected to the drum; and stop shoulder means cooperating with said stop member to stop rotation of the drum when the brakes are completely released.

2. In a hand brake mechanism, the combination with a chain-winding drum; of a brake chain connected to the drum; operating means for rotating the drum; a gravity-influenced, pivoted stop member hung on the drum; and a housing enclosing said brake mechanism, said housing having a shoulder thereon cooperating with said stop member to stop rotation of the drum when the brakes are completely released.

3. In a hand brake mechanism, the combination with a support; of a chain-winding drum rotatably mounted on said support; a pivoted stop member on the drum; a chain windable on the drum; and a fixed stop shoulder on said support engageable by said stop member for arresting rotation of the drum when the brakes are completely released, said chain when wound on the drum swinging the stop member against the drum to clear said fixed stop shoulder.

4. The combination with a drum and a cable therefor, of mechanism for preventing reverse winding of the cable on the drum, comprising a bracket carrying the mechanism, and a gravity actuated, pivoted latch lever and detent means carried by the bracket and the drum, the lever being so located that it will be held in an inactive position until the last convolution of cable is unwound from the drum.

STACY B. HASELTINE.
